CLAIM

The ornamental design for a high bay light fixture with staggered driver enclosure, as shown and described.

DESCRIPTION

FIG. 1 is a top isometric view of a first embodiment of a high bay light fixture with staggered driver enclosure;

FIG. 2 is a first end view of the first embodiment, wherein the second end view is a mirror image thereof;

FIG. 3 is a right side view of the first embodiment, wherein the left side view is a mirror image thereof;

FIG. 4 is a top side view of the first embodiment;

FIG. 5 is a bottom side view of the first embodiment;

FIG. 6 is a bottom isometric view of the first embodiment; FIGS. 7A and 7B are a top isometric view of a second embodiment of the high bay light fixture with staggered driver enclosure;

FIG. 8 is a first end view of the second embodiment, wherein the second end view is a mirror image thereof;

FIGS. 9A and 9B are a right side view of the second embodiment, wherein the left side view is a mirror image thereof;

FIGS. 10A and 10B are a top side view of the second embodiment;

FIGS. 11A and 11B are a bottom side view of the second embodiment; and,

FIGS. 12A and 12B are a bottom isometric view of the second embodiment.

The broken lines in the drawings illustrate portions of the high bay light fixture with staggered driver enclosure that form no part of the claimed design. The break lines in FIGS. 1 and 3-6 indicate that the appearance of any portion of the high bay light fixture with staggered driver enclosure between the break lines forms no part of the claimed design.
